UNITED STATES PATENT OFFICE.

GEORGE W. TANNER, OF PROVIDENCE, RHODE ISLAND.

CIGAR-MACHINE.

SPECIFICATION forming part of Letters Patent No. 340,741, dated April 27, 1886.

Application filed August 5, 1884. Serial No. 139,673. (No model.)

To all whom it may concern:

Be it known that I, GEORGE W. TANNER, of the city and county of Providence, and State of Rhode Island, have invented certain new and useful Improvements in Cigar-Machines, of which the following is a full, clear, and exact description, reference being had to the accompanying drawings, forming a part of this specification.

10 The object of my invention is to produce a machine by means of which a quantity of loose tobacco, either long or short filling, sufficient to form a cigar-bunch, is, after being bound in an inside wrapper or binder, molded and covered with the outside wrapper.

15 My invention consists in certain peculiar and novel features of construction and arrangement of various parts or devices constituting the machine, as hereinafter described and claimed.

20 In order that my invention may be fully understood, I will proceed to describe it with reference to the accompanying drawings, in which—

25 Figure 1 is front elevation of my improved machine. Fig. 2 is a top view of the same in closed condition. Fig. 3 is a similar view of the same in open condition. Fig. 4 is a transverse vertical section of the machine on the line 45 of Fig. 1, showing the machine in closed condition. Fig. 5 is a similar view on the line 4 5 of Fig. 1, showing the machine in open condition. Fig. 6 is a transverse vertical section of the machine on the line 6 6 of Fig. 1.

30 Fig. 7 is a front elevation of the inner face-plate, showing also the gears for operating the rolls. Fig. 8 is a vertical longitudinal section of the roll-gear casing, with the central shaft, the gears, and rolls in operative position, the section being taken on the line 8 8 of Fig. 2. Fig. 9 is a transverse vertical section of the machine on the line 9 9 of Fig. 1. Fig.

35 10 is a similar view on the line 10 10 of Fig. 1. Fig. 11 is a similar view on the line 11 11 of Fig. 1. Fig. 12 is a view in side elevation of the rolls and their gears in detached condition. Fig. 13 is a side elevation of the bellied cigar formed by the rolls shown in Fig. 12. Fig. 14 is a view in side elevation of a modified form of 40 rolls and their gears in detached condition. Fig. 15 is a side elevation of a straight cigar formed by the rolls shown in Fig. 14. Fig.

16 is a front elevation of one of the detachable bearing-blocks. Fig. 17 is a side elevation of the same.

55 Heretofore in making cigars the bunches have been rolled in the inside wrapper or binder and then placed in forming-molds, by which the required shape is given to the bunch. After this the molded and bound bunch was 60 supplied with its outside wrapper, either by hand or by machinery.

As I manufacture cigars, the bunches are simply rolled in the binders, and are then fed into my improved machine, which molds the 65 bound bunches and places the outside wrappers upon them.

70 The rolls are so mounted in my improved machine as to be readily removed and others substituted when cigars of different shapes and sizes are to be molded and wrapped. The cavity or mold which forms the tips of the cigars is of such form as to prevent the dislocation of the tip from the cavity or mold during the operation of the machine, and the outer 75 ends of the rolls are mounted in detachable blocks, which form a continuation of the tip-cavity, and may be quickly disconnected from the side pieces and end piece of the frame when either the blocks or the frame-pieces become worn. The surfaces of the rolls are recessed in such manner that the space inclosed by the rolls constitutes a mold in which the 80 cigar is calipered or made exactly of the size and shape required by the rolls.

85 The operating-gears and the connections for opening and closing the machine are all inclosed within the machine-frame.

In the said drawings, A designates the pedestal or base upon which the operative parts 90 of the machine are mounted. At its lower end this pedestal is provided with the foot a, by means of which the machine is screwed or bolted to the workman's bench or table.

B designates a horizontal bar or support, 95 which is cast or secured upon the upper part of the pedestal A and extends oppositely from the sides thereof.

C designates the annular frame or housing, which is secured to the left-hand end of the 100 support B by means of the downwardly-extending lug c, as is shown in Fig. 1. This housing will be particularly described herein-after. To the opposite end of the support is

secured the upright end piece, d , which carries the bearing-blocks for the outer ends of the rolls.

5 D designates the two movable side pieces, which serve to place the machine in open and closed condition.

Referring now to Figs. 2, 3, 7, and 8, I will describe the construction of the closed housing C and the operative mechanism located 10 therein. At one side of the frame C is formed a boss or bearing, c' , in which is mounted the driving-shaft E, which carries on its outer end the driving-wheel e . This wheel is peripherally grooved and carries a handle, so that 15 the machine may be operated either by power through a suitable driving belt working in the groove, or by hand applied to the handle. The driving-shaft E also carries a pinion, e' , which meshes with the pinion f' upon the counter-shaft F. The shaft F extends centrally and horizontally through a plug, C', which is threaded into the annular body of the frame C, as is clearly shown in Fig. 8. The inner face of the plug C' is recessed or depressed, as 20 shown, so as to form an annular marginal flange, c^2 .

25 C² designates a face-plate which closes the inner side of the open frame C, and is held between an annular inturned lip, c^3 , formed 30 on the inner side of the frame C, and the inner end of the flange c^2 . The shaft F is provided with a collar, f' , which abuts against the inner face of the plug C', for the purpose of holding said shaft in its normal working position. At its inner end the shaft carries a 35 pinion, f^2 , which meshes with and drives the pinions of the rolls, hereinafter described.

Upon the inner face of the plate C² is formed a segmental boss, c^4 , which is disposed as 40 shown in Fig. 11, and lies just below the center of the plate. This boss constitutes the bearings for the three lower rolls, G G' G², the spindles of which extend clear through the boss and beyond the inner side of the plate 45 C². At their ends the rolls carry, respectively, the pinions $g^3 g^4$, all of which mesh into the pinion f^2 on the shaft F. These rolls may be termed the "fixed" rolls, in contradistinction to the rolls which move toward 50 and away from each other in order to place the machine in closed and open condition. These movable rolls will be presently described.

55 C⁵ C⁶ designate two triangular or three-sided plates, each of which is pivoted at c^7 , upon the upper part of the outer side of the plate C², and through each of which is formed a slot, c^8 , through which extend the spindles of the movable rolls G³ G⁴. The spindles of these 60 rolls also extend through slots $c^9 c^6$, formed through the plate C², the arrangement being such that whichever way the rolls G³ G⁴ are moved the plates C⁵ will move with them and close the slots C⁶, so that no clippings or dust 65 may enter the space inclosed within the frame C by the plug C' and plate C². At their inner ends the spindles of the rolls G³ G⁴ carry the

pinions $g^3 g^4$, which mesh with the pinion f^2 when the machine is in closed condition, and which are carried out of engagement with the pinion f^2 when the machine is in open condition, so that when the machine is in open condition the rolls G³ G⁴ are idle, and when the machine is in closed condition the said rolls are brought into action.

75

At the driving end of the machine the movable side pieces, D, carry each a plate or extension, d' , in the upper part of each of which is an eye or hole, through which eyes extend the spindles of the rolls G³ G⁴. In the lower 80 part of each plate d' is also formed a similar eye or hole, through which extend the spindles of the fixed rolls G' G², so that the side frames are pivoted at the driving end of the machine upon the spindles of the rolls G' G². 85

Deferring, for the moment, a description of certain devices for operating the movable side pieces, D, and for holding the bound bunch under the action of the rolls, I will now describe the arrangements connected with the 90 mold for the cigar-tip and for holding the outer ends of the rolls.

H H (see Figs. 6, 16, and 17) designate the two blocks which support the outer ends of the side pieces, D, and in which the outer ends 95 of the rolls G' G² G³ G⁴ are supported. The spindles of the rolls G' G² rest in sockets or bearings which are formed in the inner side of the upright end piece, d , and upon these spindles are pivoted the detachable blocks H, 100 by means of their lugs h , each of which is formed with an eye through which the spindle of the roll passes, as is shown in Figs. 16 and 17. Just above the lug h of each block is 105 formed an extension, h' , which is separated from the lug by a curved recess, h^2 , into which works a correspondingly-shaped extension upon the end piece, d , which serves to guide the block in its movements. A recess or socket is formed in the extension of each block H, and 110 these eyes serve as bearings for the spindles of the rolls G³ G⁴, as is shown in Fig. 6. The spindle of the roll G has its bearings in the end piece, d , as is shown in Fig. 6.

d³ designates the cavity or mold, which receives the point or tip of the bound bunch during the operation of molding and wrapping. This cavity or mold is of such form as to correspond to the intended shape of the tip and is formed in the upper end of the upright end 115 piece, d . A careful examination of Fig. 6 will disclose the fact that the inner margin-line of the cavity d³ describes a curve of more than half a circle in extent, and this indicates the general form of the cavity, which is of course wider and deeper at its inner end and decreases in width and depth toward its outer end, which is a mere point. This peculiar form of the mold-cavity constitutes an important and valuable feature of my invention, and its purpose will be hereinafter fully explained. Those points of the blocks H which lie directly above the cavity d³ when the machine is in closed condition are formed with curved recesses, which constitute 120

125

130

a continuation of the contour of the cavity d^3 and correspond with it in form in such manner as to complete the circular recess in which the tip is formed. The upper portion of the 5 block H, at the left side of the end piece in Fig. 6, is formed with an extension, h^3 , which overlaps the contiguous face of the opposite block, and thus completely incloses the recess for the tip. Each block H is formed on its 10 inner face with two pins, h^4 , which fit into corresponding recesses in the contiguous ends of the side pieces, D.

h^5 designates a screw, which passes from without longitudinally through the block and enters a threaded cavity in the end of the side piece, D, so that by the combined action of the screw and pins of each block it is secured to the side piece and moves therewith. The required movements of the side pieces, D, are 15 produced by means of a rod, I, which extends vertically upward into the pedestal A, and to the lower end of which may be connected a foot-lever. Within the pedestal A, which is hollow, is placed an inverted cup-shaped slide, 20 I', within which and surrounding the rod I is confined a spiral spring, i, which acts expansively to hold the slide I' in elevated condition. Upon the upper end of the slide I' are formed two oppositely-extending lugs, i', each 25 of which works in a vertical slot in the pedestal A. To the outer ends of the lugs i' are pivoted the lower ends of the links i'', the upper ends of which are hinged to lugs d^4 , which are formed upon the side pieces, D. Thus it 30 will be seen that the machine remains normally in closed condition, owing to the action of the spring i, and that it is opened by pulling downward upon the rod I. The upward movement of the slide I' is limited by a screw, j, which 35 extends downward through a cap, J, secured upon the top of the standard A. The screw j is held at any desired point of adjustment by a locking-nut, j'.

K designates a gage or slide which lies within 40 the space inclosed by the rolls, and the object of which is to press against the lighting end of the bound bunch during the operation of molding and wrapping, for the purpose of 45 pressing and holding the tip into the cavity d^3 . This gage or slide is mounted on a shaft, k', through the medium of an arm, k, and the shaft k' works in a recess or channel in the 50 front side piece D. A handle, K', by which the gage or slide is operated, is secured to the shaft k' and extends through a longitudinal slot in the piece D.

In Figs. 12 and 14 I have shown two styles of rolls. That shown in Fig. 12 is for the purpose of forming the bellied cigar shown in Fig. 55 13, and the depressions in the rolls are of such form as to correspond with the shape of the cigar—that is to say, such depressions are deep and comparatively short. The rolls shown in Fig. 14 are for forming the straight cigar shown 60 in Fig. 15, and the depressions are comparatively shallow and longer. The purpose of

illustrating these two sets of rolls is to show the purpose of so constructing the machine as to render it capable of readily receiving different sets of rolls, which is accomplished by 70 unscrewing the plug C', and withdrawing the face-plate C' and one set of rolls from the frame C, and then inserting another similar face-plate with a different set of rolls, after which the plug C', with its counter-shaft F, is screwed 75 into the frame C. Previous to removing the plug C' with its counter-shaft it is necessary to remove the driving-wheel and its attached pinion from the shaft E, which is readily done by removing the screw which usually secures 80 such wheels to their shafts. The rolls, when the machine is in closed condition and is in operation, caliper the cigars—that is to say, form them into uniform shape during the molding.

The machine is compact, simple, and durable in construction, and is easily operated.

All of the working parts of the machine are protected against the entrance of dirt, dust, or pieces of tobacco, and such parts as may 90 eventually become worn or injured in any way may be quickly removed, and new parts may be readily substituted.

The operation of my improved machine is as follows: The proper set of rolls being placed 95 in the machine, the side pieces, D, are separated by a downward movement of the rod I, and the bound bunch is placed upon the roll G. The pressure upon the rod I is then removed, and the spring i is permitted to close 100 the machine. The gage or slide K is now brought up against the lighting end of the bunch, and the tip of said bunch is gradually forced into the mold d^3 . The machine is now 105 placed in motion, and as the bunch is rotated the rolls caliper it and mold it into shape. The wrapper is then curled upon the bunch. The workman has only to properly guide the wrapper into the machine over the front side piece D, and the rolls will properly lay the wrapper. 110 Owing to the peculiar form of the cavity d^3 , the tip cannot possibly be thrown out of the cavity during the rotation of the bunch, and consequently the wrapper will be properly rolled upon the tip. After the wrapping, 115 pressure is again applied to the rod I, the cigar is taken out of the machine, and the above-described operations are repeated.

I do not wish to be understood as confining myself exclusively to the precise construction 120 of parts as above described, as my invention contemplates numerous modifications in mere details of construction—as, for instance, the bearing-blocks H may be formed integral with the side pieces, D, without changing the peculiar character of the tip cavity or mold, and without lessening the efficiency of the machine.

Having thus described my invention, I claim as new and desire to secure by Letters Patent—

1. In a cigar-machine, the combination, with 125 a standard located at one end of the molding-rolls, and having a tip-cavity, d^3 , of a pair of

co-operating separable blocks suitably recessed and pivoted to said standard, for the purpose described.

2. The combination, with a standard having a tip-cavity, d^3 , and located at one end of the rolls contained in the movable side pieces, which are each secured to a separable block suitably recessed and pivoted to said standard, of a sliding gage, K, located at the other end of said rolls, for the purpose described.

3. In a cigar-machine, a pair of blocks separably secured to the movable side pieces of the frame and containing the bearings for the rolls, and also provided with recesses to complete the form of the tip-cavity, substantially as described.

4. The combination, with the frame A B, of the closed housing C, the movable side pieces, D, and the separable blocks H, constructed and arranged as described.

5. The combination, with the frame A B, the closed housing C, the side pieces, D, and the separable blocks H, of the shaft F, carrying the pinions f^2 , and the rolls G G' G² G³ G⁴, carrying the pinions g g' g² g³ g⁴, and the connections for operating the side pieces, as described.

6. The combination, with the pedestal A, the support B, carrying the housing C and end piece, d, side pieces, D, and the hinged blocks H, of the driving-shaft E, carrying the pinion e', the plug C', carrying the shaft F, with its pinions f f², the face-plate C², the rolls G G' G² G³ G⁴, with their pinions, the blocks H, and the rod I, slide I', spring i, and links i², all con-

structed and arranged substantially as shown and described.

7. The combination, with the pedestal A and the side pieces of the frame, of the cap J, the screw j, the lock-nut j', the arms i², the slide I', and the stem I, as set forth.

8. In a cigar-machine, the combination, with the closed housing having the slotted face-plate and the movable rolls, of the pivoted plates connected with said rolls and arranged to close the slots in the face-plate when the machine is opened, substantially as described.

9. The combination, in a cigar-machine, of the pedestal and support, the fixed rolls mounted thereon, the side pieces supporting the movable rolls, and the spring-pressed slide I', the arms, and the treadle, as and for the purposes set forth.

10. The combination, with the pedestal A, the support B, carrying the housing C and end piece, d, side pieces, D, hinged block H, and gage or slide K, of the driving-shaft E, carrying the pinion e', the plug C', carrying shaft F, with its pinions f f², the face-plate C², the rolls G G' G² G³ G⁴, with their pinions, the blocks H, the rod I, slide I', spring i, and links i², as described.

11. The combination, with the standard d, having the tip-cavity d^3 , of the separable blocks H H, pivoted to said standard d, for the purpose described.

GEORGE W. TANNER.
